LEATHER JACKET SLEEVE

Sam Slater, San Francisco, Calif., assignor to S.
Slater and Son, San Francisco, Calif., a corpora-
tion of California

Application April 15, 1952, Serial No. 282,343

1 Claim. (Cl. 2—270)

1

The invention relates to sport or utility jacket sleeves such as made of leather and relates more particularly to the cuff portions of such sleeves.

In so-called leather jackets, the sleeves as well as the body portions are ordinarily formed of leather throughout. Some users however object to an all leather sleeve, particularly for the cuff or outer end portion, because of the non-elastic nature of the leather and therefore of the practical impossibility of providing a snug-fitting sleeve-end which would be readily slipped on and off the arm of the wearer. To overcome such objection, some manufacturers have resorted to providing a cuff entirely of knitted material which was secured at one end to the sleeve body. Such a cuff is made of smaller circumference than the leather sleeve end to which it is attached, so as to thereby snugly fit and at the same time is sufficiently elastic or expansible to permit insertion or withdrawal of the arm, therethru. The all-knitted cuff however has one disadvantage in that it does not possess the wearing qualities of a leather sleeve end or cuff, and appreciably reduces the life of the jacket unless the cuff is repeatedly replaced.

In view of the above, it is an object of the present invention to provide a cuff for the leather jacket sleeves which will have all of the wearing qualities of an all-leather cuff or sleeve and at the same time will afford snugness of fit as well as the ease of insertion or removal of the arm through the cuff as permitted with an all knit cuff.

Another object of the invention is to provide a cuff with sections of leather and of knitted material, which will be so formed and seamed to one another as to avoid any discomfort to the wearer.

The invention possesses other objects and features of advantage, some of which, with the foregoing, will be set forth in the following description of the preferred form of the invention which is illustrated in the drawing accompanying and forming part of the specification. It is to be understood however, that variations in the showing made by the said drawing and description may be adopted within the scope of the invention as set forth in the claim.

Referring to said drawings:

Figure 1 is an elevational view of the lower portion of the underside body of the sleeve as provided with the cuff of my invention.

Figure 2 is an end view of the lower end of the cuff.

Figure 3 is a transverse sectional view of the

2

cuff taken on the line 3—3 of Figure 1 and showing part of the adjacent portion of the jacket body.

Figure 4 is a longitudinal sectional view on line 5 4—4 of Figure 3.

Figure 5 is a view similar to Figure 1, but showing the outer-body of the sleeve.

Figure 6 is a side view of the sleeve with a somewhat modified form of the cuff portion.

10 In the drawings, the cuff 5 of my invention is shown in connection with a sleeve 6 of a utility or sport jacket 1 of the type in which both the sleeve and body portion of the jacket are formed with an outer covering of leather or the like.

15 The sleeve is usually formed of two main sections, to wit, an outer or front section 8 and an under or rear section 9, the section 9 being disposed for the most part generally opposite the adjacent portion of the jacket body, while the section 8 is on the outer or more exposed side of the sleeve. The front section 8 is usually of somewhat greater width than the section 9, and both sections are stitched together at their side edges to define seams 12 and 13, the seam 12 being arranged to lie nearer the jacket body. As

20 the leather is relatively inelastic, the sections are formed fairly full so as to but loosely fit the arm of the wearer. However, to provide for proper comfort of the wearer, the outer or open end of the sleeve should fit snugly about the wearer's wrist, and it is for this reason that the sleeve is foreshortened and a cuff of elastic material has been generally provided for the open or free end of the sleeve. Such elastic cuff has usually 25 been in the form of a band of knitted or webbing material with the ribs extending lengthwise of the sleeve so as to afford greater expansion or elasticity circumferentially.

As will be understood, a leather jacket is 30 adapted for rugged use, and the simple knitted cuff while filling most of the requirements previously explained, is unsuited for the wear which the end or cuff portion of the sleeve is usually subjected in a garment of this character. Particular 35

40 particularly is the wear on the under arm portion of the cuff, that is the portion which normally rubs against the jacket body and the exposed sharp edged "zipper" connections thereon. It is not uncommon to require several replacements 45 of the knitted cuffs during the normal period of wear of the jacket, and while the leather on the sleeves and body of the jacket remain comparatively intact.

50 In accordance with my invention, I overcome such disadvantages by inserting a section 14 of

leather for the part of the cuff subjected to the greater use and retaining for the remainder of the cuff a section 16 of the knitted or webbing material. The leather cuff section 14 is relatively narrow as compared to the knitted cuff section 16 so that the elasticity or expansibility of the cuff as a whole is not materially reduced. At the same time since the webbing comprises the greater circumferential portion of the cuff and forms the front and for the most part the sides of the cuff, the leather insert will be hardly visible when the jacket is being worn.

The sections 14 and 16 are secured together along their adjoining edges and it is important to note that leather section 14 as well as section 16 is attached directly to the sleeve body as in this manner the leather section will not be dependent on the knitted section for support but will in fact provide more support for the webbing. The particular construction and attachment of the parts will be clear from Figures 3 and 4 of the drawings. As will be seen from these figures, each of the cuff sections 14 and 16 is of double thickness made so by folding one layer of material upon another, the bend occurring at the outer end of the cuff. The side edge portions 18 and 19 of the leather section are inserted between the adjoining side edge portions 21 and 22 of the webbing, and to eliminate the exposure of the raw edges of the webbing, the portions 21 and 22 are stitched to the portions 18 and 19 while in matched relation and then folded back. In this way, only the relatively smooth fold of portions 21 and 22 will be exposed at the joint of the sections and there will be no danger of fraying the edges of the webbing or of any chafing of the wrist of the wearer. The inner edge portions 23 and 24 of sections 14 and 16 respectively, are each seamed on the outer side directly to the leather material 26 of the sleeve body and on the inner side directly to the sleeve lining 27. With the sections thus made and secured, the cuff will be substantially as sturdy as an all-leather cuff, yet as flexible and elastic as one formed entirely of the knitted material.

Attention is also directed to the fact that both seams which connect section 14 to section 16 lie entirely inwardly of the seams which connect the under and outer sections of the sleeve body. This is of importance since it avoids the need of, and the attendant bulging caused by, intersecting seams and folds of leather.

In Figure 6, I have shown a slightly modified form of the invention. In this embodiment the leather section of the cuff instead of being in the form of a separate insert, is formed as an integral extension 28 of the leather forming the body of the sleeve.

I claim:

15 A jacket sleeve having a relatively large opening at the lower edge thereof, the sleeve formed of a relatively inelastic material; a constricting cuff for said sleeve comprising two sections, one of which is formed of material corresponding to 20 the sleeve material and joined to the sleeve along a portion of the lower edge thereof, and a second section formed of a relatively elastic material secured to said sleeve along the remaining portion of said lower edge and secured at its opposite 25 sides to said first section for substantially the entire length of the second section, said first section being positioned on the inside of said sleeve normally adjacent the main body of the jacket.
